(57) **CLAIM**

The ornamental design for a toy bridge clip, as shown and described.

DESCRIPTION

FIG. 1 is a top perspective view of the toy bridge clip in accordance with a first embodiment of our new design;

FIG. 2 is a top plan view thereof;

FIG. 3 is a front elevation view thereof, the rear elevation view being identical thereto;

FIG. 4 is a left side elevation view thereof, the right side elevation view being identical thereto;

FIG. 5 is a bottom plan view thereof;

FIG. 6 is a top perspective view of the toy bridge clip in accordance with a second embodiment of our new design;

FIG. 7 is a top plan view thereof;

FIG. 8 is a front elevation view thereof, the rear elevation view being identical thereto;

FIG. 9 is a left side elevation view thereof, the right side elevation view being identical thereto; and,

FIG. 10 is a bottom plan view thereof.

The broken lines illustrate portions of the toy bridge clip that form no part of the claimed design.

The oblique shade lines in FIGS. 6-10 represent a transparent surface or translucent surface and not surface ornamentation.
